ROAD PAVEMENT JOINT CLEANING AND FINISHING TOOL

Filed Dec. 26, 1930

UNITED STATES PATENT OFFICE

EDWARD M. CRUZ, OF ALPINE, CALIFORNIA

ROAD PAVEMENT JOINT CLEANING AND FINISHING TOOL

Application filed December 26, 1930. Serial No. 504,825.

My invention relates to finishing tools particularly adapted for use on concrete pavements, and the objects of my invention are:

First, to provide a tool by means of which the contiguous edges of adjacent paving sections may be simultaneously rounded off;

Second, to provide a tool of this character which removes concrete from the upper surface of the expansion strips placed between adjacent sections, and insures a clear gap between such sections;

Third, to provide a device of this character which is self-adjusting;

Fourth, to provide a device of this character for alining the marginal portions of adjacent pavement sections; and

Fifth, to provide a device of this character which is easily handled, simple in operation, rugged in construction, and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawing and to the characters of reference thereon, which form a part of this application, in which:

Figure 1 is a perspective view of my novel tool, showing its application to the pavement, certain portions being broken away in order to facilitate the illustration; Fig. 2 is a sectional view taken along the line 2—2 in Fig. 1; Fig. 3 is a detailed view in section taken along the line 3—3 in Fig. 2; and Fig. 4 is a section taken along the line 4—4 in Fig. 3, showing the housing, head member and tongue only with the remaining portions omitted to facilitate the illustration.

Similar characters of reference refer to similar parts and portions throughout the several views of the drawing.

The smoothing plates 1, connecting straps 2, handle 3, housing 4, spring 5, and tongue 6 form the principal parts and portions of my novel tool.

The plates 1 may be bent in form from

sheet metal plates of sufficient thickness to insure adequate rigidity, the corner portions 1c being bent around a radius so as to form a curved surface for rounding the edge of the pavement. The plates are positioned with their shorter arms 1b in parallel spaced relation and their longer arms 1a in substantial alinement but oppositely directed, as clearly shown in Figs. 1 and 2. The spacing of the plates 1 is so dimensioned that the portions 1b will readily pass over the expansion strip S placed between adjacent pavement sections P1 and P2.

The plates are held rigidly in the desired position by means of the straps 2, which are secured to the portions 1a of the plates, as by riveting or welding, or in any other suitable manner. The straps 2 are preferably positioned over the end marginal portions of the plates 1, and are preferably provided with an arched portion 2a bridging the gap between the portions 1b.

A handle 3 of substantially U-shaped form is secured at its ends to said bridge portion 2a of the connecting straps 2, and is thus positioned directly over the gap between the plates 1.

At a position substantially in the center of the plates 1 is placed a box-shaped housing member 4. This housing member 4 consists essentially of two portions, the portion 4a comprising an upper end wall 4b and three side walls 4c. One of said side walls has a right angularly extending base portion 4d. The open side of the housing is covered by means of the cover portion 4e, which has a right angularly extending base portion 4f complementary to the portion 4d of the housing. At the upper end of the cover 4e is a strap portion 4g bent at right angles to the portion 4e and extending over the upper end 4b of the housing. The extreme end portion of the strap 4g is bent downwardly over the opposite side wall 4c, as indicated clearly in Fig. 2. The marginal portions 4h of the cover 4e are bent at right angles to the portion 4e, and embrace the side walls 4c of the housing, as shown in Fig. 4. Screws 7 are provided for securing the base portions 4d and 4f to the plates 1.

- A substantially rectangular sub-base plate 8 extends under the housing and is separated from the base portions 4d and 4f thereof and the plate portions 1a by means of felt strips 5 9. The plate 8 is provided with a rectangular slot 8a of a length substantially equal to the gap between the plates portions 1b, and extending transversely of said plate portions 1b, in alignment with said gap.
- 10 Within the housing 4, is a substantially helical spring 5, which bears against the upper end wall 4b of the housing and against a head member 6a of a tongue 6. The tongue 6 is in the form of a stiff rectangular strip, preferably of metal, and is adapted to project through the slot 8a in the plate 8 and into the gap between the plate portions 1b, as clearly shown in Fig. 2.

20 The head member 6a of the tongue 6 is of a shape conforming to the plan of the housing 4, and is adapted to slide between the walls 4b thereof without binding. The lower end of the tongue 6 is cut square so as to rest evenly on the upper surface of the expansion strips 25 S, as indicated in Fig. 2.

30 The spring 5 is adapted to force the tongue 6 against the upper surface of the strips S, as the tool is moved along the portions 1b of the plate 1 bearing against the upper side margins of the strips S during this operation. The tongue 6 naturally follows any irregularity of the upper surface of the strips S, so that any concrete lying over the upper surface of the strips will be scraped along 35 by means of the tongue as the tool is moved.

40 A small quantity of grease is placed inside the housing in order to keep the tongue lubricated and prevent ingress of water or cement while the tool is in use. As occasion demands said grease may be introduced by removing the cover portion 4e of the housing, which may be readily done by removing the screw 7 by means of which it is held in place.

45 The application of my tool is as follows: After the final layer of concrete has been poured on adjacent pavement sections separated by the expansion strip S, the upper surface of which lies slightly below the upper surface of the pavement, I place my tool over the expansion strip, with the portions 1b bearing against the sides thereof, and the end of the tongue 6 bearing against the upper surface of the strip. I then move the tool lengthwise with the strip over the concrete surface, whereby the horizontal portions 1a smooth out the upper surface of the concrete, bringing the opposite marginal portions of adjacent sections accurately in alignment and round the edges in approved manner. Any concrete lying on the upper surface of the expansion strips S or finding its way between the plates during the manipulation of the tool will be effectively cleared by means of the tongue 6, which, as previously stated, is adapted to follow any

irregularity of the upper surface of the expansion strips.

Since pavement sections finished by means of my tool are separated by a uniform gap directly over the expansion strip, the latter 70 is able to function properly, thereby preventing the cracking or breaking off of the pavement at the joint of adjacent sections which may happen when concrete is allowed to bridge the gap. Likewise the accurate alignment of the marginal portions of adjacent sections ensures an even passage of vehicle wheels over the gap between sections, eliminating shock and hammer blows which 75 eventually result in damage to the pavement 80 edges.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In an expansion joint cleaning and smoothing tool, a pair of plates having smoothing portions occupying a common plane and curved marginal portions positioned in spaced apart parallel relation for rounding the contiguous edges of adjacent pavement sections, and scraper means extending between said curved portions adapted to bear against the upper surface of the expansion strip between said pavement sections.

2. In a pavement smoothing tool, a pair of plates having smoothing portions occupying a common plane and curved marginal portions positioned in spaced apart parallel relation for rounding the contiguous corners of adjacent pavement sections, and a vertically reciprocable tongue supported over said plates and projecting between said curved portions adapted to bear against the upper surface of the expansion strip between said pavement sections and follow the irregularities thereof on movement of said tool.

3. In a pavement smoothing tool for clearing a gap formed by an expansion strip disposed between adjacent freshly poured pavement sections, a pair of spaced apart guide plates adapted to bear against contiguous edges of said pavement sections, and scraper means extending between said guide plates and into said gap for removing undesirable matter from said expansion strip in said gap on movement of said tool along said gap.

4. In a pavement smoothing tool for clearing a gap between adjacent freshly poured pavement sections, a pair of spaced apart guide plates of arcuate cross section adapted to bear against and rounded contiguous edges

of said pavement, a housing supported on said plates, a tongue extending from said housing into said gap between said plates, and spring means in said housing for resiliently supporting said tongue in extended position.

5. In a pavement smoothing tool for clearing a gap formed by an expansion joint strip disposed between adjacent freshly poured 10 pavement sections, a pair of spaced apart guide plates of arcuate cross section adapted to bear against the rounded contiguous edges of said pavement, a housing supported on said plates and a tongue member reciprocally 15 mounted in said housing and one end extending from said housing into said gap between said plates and engaging the edge of said expansion strip.

In testimony whereof, I have hereunto set 20 my hand at San Diego, California, this 6th day of December, 1930.

EDWARD M. CRUZ.
